UNITED STATES PATENT OFFICE.

CORNELIUS HAYES, OF OSWEGO, NEW YORK.

GRAIN-ELEVATOR.

SPECIFICATION forming part of Letters Patent No. 317,353, dated May 5, 1885.

Application filed March 28, 1885. (No model.)

To all whom it may concern:

Be it known that I, CORNELIUS HAYES, of Oswego, in the county of Oswego, in the State of New York, have invented new and useful 5 Improvements in Grain-Elevators, of which the following, taken in connection with the accompanying drawings, is a full, clear, and exact description.

This invention relates to improvements in 10 that class of elevators which are used for removing grain, ground land-plaster, and other granular or ground substances from the hold of a vessel, or from the lower part of a storehouse to the upper part of the latter. In the 15 operation of these elevators, the men who work around the foot of the elevator are subjected to great inconvenience and injurious effects incident to the inhaling of the dust caused by the agitation of the substance in feeding the 20 same to the foot of the elevator.

It is to overcome the aforesaid difficulties, and also to facilitate the operation of feeding the substance to the foot of the elevator, which 25 my invention has for its object; and to that end my invention consists in the novel construction and combination of parts, as herein-after fully described, and specifically set forth in the claims.

In the annexed drawings, Figure 1 is an elevation of an elevator provided with my improvements. Fig. 2 is a transverse section on line xx , Fig. 1. Fig. 3 is an enlarged detached perspective view of the coupling of the ventiduct and its extension, and Fig. 4 is a side elevation of the same.

Similar letters of reference indicate corresponding parts.

A and A' represent the so-called "elevator-legs," in which the elevator-buckets travel in 40 the usual and well-known manner, said elevator-legs being here represented introduced into the hold of a boat, the upper end of the elevator projecting above the boat, and having its discharge-spout s extended into a building, as 45 indicated by dotted lines in Fig. 1 of the drawings.

P designates a ventiduct consisting of a pipe, which, for protection from injury, is arranged 50 between the elevator-legs A A', and extended lengthwise thereof. The lower end of the ventiduct is secured to the leg A' by clips or bands

n , and terminates with a flaring receiving-mouth, m , near the foot of the elevator-legs, and the discharge end of the ventiduct is extended toward the top of the elevator, where 55 it is attached to an iron plate, b , which is bolted onto the top of a wooden plate, a , secured between the elevator-legs A A', the plate b being provided with an opening corresponding to the interior of the ventiduct, and having around said opening a collar, c , into which the end of the ventiduct P is inserted. The top of the plate b is provided with guides $d d$, between which slides a plate, e , and this plate is provided with an opening and a collar, e' , around said opening, similar to that of the plate b .

To the collar e' is attached a hose or other flexible pipe-extension, P', and the latter is connected with the induction-port of an exhaust-fan, F, which, when in motion, serves to draw the dust from around the foot of the elevator into the mouth m of the ventiduct P, and through said duct and its extension P', and expel the dust through the discharge-pipe R 75 of the fan, as indicated by arrows in Fig. 1 of the drawings. This suction through the ventiduct not only carries away the dust, but also creates a circulation of air from the exterior of the boat to the hold thereof, and thus effectually relieves the laborers in the boat of the suffocating effect which they have hitherto been subjected to.

The coupling and uncoupling of the pipes P P' is readily effected by sliding the plate e 85 onto and off from the plate b . This simple and convenient coupling of the two pipes is essential, inasmuch as the elevator has to be lowered into and raised out of the boat.

In order to facilitate the operation of feeding to the foot of the elevator the substance to be elevated, I provide the foot of the elevator with side openings, o , and extend from said openings troughs B B, placed in an inclined position, as shown in Fig. 1 of the drawings. 95 By throwing the grain or other substance into the trough, said substance moves by its gravity to the foot of the elevator, thus saving the labor of shoveling the aforesaid substance the distance over which the troughs are extended, 100 and also producing less dust in transferring the substance.

Having described my invention, what I claim as new, and desire to secure by Letters Patent, is—

1. The combination, with the elevator-legs A A', of a ventiduct extended from the foot of said elevator to the upper part thereof and a hose or pipe-extension detachably connected with the upper end of the ventiduct, as and for the purpose specified.

2. In combination with the elevator-legs A A', the pipe P, secured between said legs, and having its receiving end near the foot of the same, and its discharge end extending toward the top of the elevator, a hose or pipe extension detachably connected with the pipe P at the upper part of the elevator, and an exhaust-fan connected with said pipe-extension, substantially as and for the purpose set forth.

3. In combination with the elevator-legs A A', the pipe P, arranged between said legs and having its receiving-mouth near the foot of the same, the plate a, secured between the elevator-legs near the upper end thereof, a pipe-coupling on said plate, having the upper end of the pipe P connected with it, a hose or pipe extension connected with said coupling, and an exhaust-fan connected with the pipe-extension, substantially as described and shown.

4. In combination with the elevator-legs A A', the pipe P, arranged between said legs and having its receiving-mouth near the foot

of the same, the plate a, secured between the elevator-legs near the upper end thereof, the plate b, attached to plate a, and having an opening with a collar, c, connected to the upper 35 end of pipe P, guides d d on the plate b, the plate e, sliding between said guides and provided with an opening, and a collar, e', around said opening, and the pipe-extension P', connected with the collar e', substantially as described and shown.

5. The combination, with the elevator-legs A A', of the troughs B B, extended from the foot of the elevator, substantially as and for the purpose set forth.

6. The combination, with the elevator-legs A A', of the ventiduct P, having its receiving-mouth at or near the foot of the elevator, and its discharge end extending toward the top of the elevator, and the troughs B B, extending 50 from the foot of the elevator, substantially as described and shown, for the purpose set forth.

In testimony whereof I have hereunto signed my name and affixed my seal, in the presence of two attesting witnesses, at Syracuse, in the 55 county of Onondaga, in the State of New York, this 12th day of March, 1885.

CORNELIUS HAYES. [L. S.]

Witnesses:

FREDERICK H. GIBBS,
WILLIAM C. RAYMOND.
